ARM REST COVER

Walter E. Jeckell, Huntington Park, Calif.

Application March 29, 1954, Serial No. 29,731

Term of patent 14 years

(Cl. D14—6)

FIG. 1

FIG. 2

FIG. 3

Fig. 1 is a front elevational view of an arm rest cover embodying my new design;

Fig. 2 is a rear elevational view of the same;

Fig. 3 is a top view of the same; and

Fig. 4 is an end view of the same.

I claim:

The ornamental design for an arm rest cover, substantially as shown.
